UNITED STATES PATENT OFFICE.

HOVCEP SARAFIAN, OF TITUSVILLE, PENNSYLVANIA.

DESIGN FOR ORIENTAL CARPET.

SPECIFICATION forming part of Design No. 32,864, dated June 19, 1900.

Application filed April 20, 1900. Serial No. 13,665. Term of patent 7 years.

To all whom it may concern:

Be it known that I, HOVCEP SARAFIAN, a citizen of the United States, and a resident of Titusville, in the county of Crawford and State of Pennsylvania, have invented and produced a new and original Design for an Oriental Carpet, of which the following is a full, clear, and exact description.

Reference is to be had to the accompanying drawing, forming a part of this specification, in which the figure is a face view of an oriental carpet, showing my design.

The leading feature of the design consists in the design forming the subject-matter of the accompanying illustration.

The design in its entirety consists of a background A in contrast to a configuration simulating basket-work, and consisting, essentially, of outer parallel straight border-stitches

B, between which appear alternately-arranged short branch stitches B'. The short contrasting stitches are comparatively short with respect to their width, which in connection with the border-strokes B, which are straight and parallel, as before described, operates to give the carpet a distinctive appearance.

Having thus fully described my invention, I claim as new and desire to secure by Letters Patent—

The design for an oriental carpet, as herein shown and described.

In testimony whereof I have signed my name to this specification in the presence of two subscribing witnesses.

HOVCEP SARAFIAN.
